UNITED STATES PATENT OFFICE.

RAYMOND CALPIN, OF EVERETT, MASSACHUSETTS, ASSIGNOR TO A. S. CAMPBELL COMPANY, OF EAST BOSTON, MASSACHUSETTS, A CORPORATION OF MASSACHUSETTS.

CURTAIN WINDOW.

Application filed April 14, 1923. Serial No. 632,108.

This invention pertains to improvements in curtain windows. It is among the objects of the invention to provide a curtain window installation of inexpensive construction, facile of assembly and of pleasing appearance, while at the same time providing a very secure connection between glass, frame and curtain. Reference is hereby made to applicant's co-pending application, Serial No. 632,107, filed April 14, 1923.

10 In the drawings, which show a preferred form of my invention, including a modification:

Figure 1 is an elevation of a curtain window assembled with its carrying fabric;

15 Fig. 2 is a section on the line 2—2 of Fig. 1;

Fig. 3 is a partial section on the same line as Fig. 2, showing the relation of the parts 20 at an intermediate stage of the assembling operation;

Fig. 4 is a plan view of a portion of one of the frame parts;

Fig. 5 is a side elevation of the frame part 25 shown in Fig. 4;

Fig. 6 is a plan view of the other frame part; and

Fig. 7 is a section through a side of a frame constituting a modification of my invention.

30 Referring to Figs. 1 through 6, I have shown a curtain window including a glass 8 secured to its carrying fabric, herein shown as the curtain 9 of an automobile, by frames 35 including a prong-providing frame 10 and a prong-receiving frame 11. The prong-providing frame 10 resembles that shown in my co-pending application Serial No. 632,107 filed herewith, being formed of a single sheet 40 of metal bent back at both sides to present a double thickness, with rounded inner and outer edges, presenting a relatively extended inner surface to the adjacent curtain material, and pressing the latter against the adjacent surface of the glass 8 and against an 45 opposed relatively extended curtain-engaging surface of the opposed frame. The prongs project from an edge of the material forming the prong-providing frame, preferably from what was, prior to bending of the frame to shape, an inner edge of the blank. The prong is thus considerably removed from both the inner and outer edges 50 of its frame and well adapted to enter a

prong-receiving aperture in the prong-receiving frame at a distance from both edges of the latter frame, thereby to clamp the curtain material, for a considerable area on either side of the prongs, between surfaces of the opposed frames.

55 The prong-providing frame (except the modification in Fig. 7) is provided with plural stiffening ribs formed by two beads, intermediate of and generally parallel to its edges, such beads, however, so spaced as to permit a strong backing for the prongs from the outer portion of the prong-carrying frame, there being no opportunity for the prongs to yield during assembly, with resultant looseness of grip on the curtain which 60 would promote working loose of the frames, and wear or tearing of the curtain material by the prongs which pass through it. Also an opportunity is provided, where desired, to permit soldering of the prong-carrying 65 flange of the frame to the overlying metal to which said flange is otherwise connected only at its edge. The provision of the stiffening beads on the prong-providing frame is optional, as the thickness of the metal may 70 if desired be relied upon or, better, the stiffening bead or ridge may be provided entirely on the prong-receiving frame, where it may serve a double function, as its inner 75 surface may provide a prong-turning anvil 80 as hereinafter more fully described.

75 The glass is preferably received in an offset entirely located in the frame located on the same side of the curtain material as the glass, this frame herein shown as the prong-receiving frame 11 presenting a glass-receiving offset flange 20, a base flange 21 apertured to permit passage of the prongs therethrough and an outer edge turned back on itself prior to assembly being pre-formed 85 to provide at the same time a prong-concealing top 22 and to provide a prong-turning 90 surface or anvil, adapted to curl the prong, preferably toward the glass, until it presses very strongly against the base flange 21, forcing this strongly toward the prong-providing frame. The prongs are preferably 95 relatively weak adjacent their ends to facilitate starting of the prong-turning operation without marking the exterior of the prong-concealing flange 22. In the embodiment of my invention shown in Figs. 2 and 100 3, the prong-turning anvil may be either 105

isolated struck-up portions, one above each of the prong-receiving openings 24, or they may be a continuous ridge extending entirely around the frame, which latter construction is perhaps superior in appearance. In the embodiment of my invention shown in Fig. 7, the prong-turning is effected by the interior of a continuous ridge of sufficient height to stiffen the prong-receiving frame considerably and to warrant, if desired, the omission of any stiffening ridge on the prong-providing frame.

To permit convenient shipping of the frames from the factory where made to the point of installation, I may enter the prongs in the prong-receiving openings, any injury from excess pressure where shipping in quantity being avoided, if present, by spacing projections 25, usually four in number, distributed about the frames and not fitting any corresponding holes in the prong-receiving frame. These spacing projections, if used, are preferably scored at their base so that they may be easily broken off by bending laterally prior to assembly of the curtain installation.

The prongs, as illustrated, should be deflected toward the glass to provide a secure grip thereon, the pressure ordinarily applied by a suitable press at the place of assembly, the dies engaging beneath the prong-providing frame and above the prong-receiving frame, and exerting pressure on the frames near the prongs but not on the glass except as transmitted through the glass-receiving flange, which has sufficient resiliency, coupled with that of the cushioning adhesive tape 30 and confined edge of the curtain material, to prevent breakage of the glass even when, as occasionally happens, the latter is not flat but somewhat warped.

The glass, adhesive tape and frame and curtain surfaces adjacent thereto should be coated with a suitable adhesive cement prior to assembly.

While I have shown and described a preferred embodiment of my invention, it will be understood that I have done so for purposes of clarification, not of limitation, and that my invention comprehends constructions of the various types defined by the following claims.

Claims:

1. A curtain window installation comprising, in combination, opposed frames presenting opposed extended surfaces between which the curtain fabric may be gripped, prongs extending from one of said frames intermediate of one of said surfaces, prong-receiving apertures in the other of said frames intermediate the other of said surfaces and a prong turning and concealing portion overlying said prong-receiving apertures.

2. A curtain window installation comprising,

ing, in combination, opposed frames presenting opposed extended surfaces between which the curtain fabric may be gripped, prongs extending from one of said frames intermediate of one of said surfaces, prong-receiving apertures in the other of said frames intermediate the other of said surfaces and integral with the frame presenting said prong-receiving apertures and a prong turning and concealing portion overlying said prong-receiving apertures.

3. A curtain window installation comprising, in combination, opposed frames presenting opposed extended surfaces between which the curtain fabric may be gripped, prongs extending from one of said frames intermediate of one of said surfaces, prong-receiving apertures in the other of said frames intermediate the other of said surfaces and a prong turning and concealing portion overlying said prong-receiving apertures, said prong turning and concealing portion providing a stiffening rib.

4. A curtain window frame element presenting a base portion having a substantial area for engagement with the curtain fabric, a prong concealing and turning portion integral with said base portion, and an angular glass retaining portion integral with one of said portions.

5. A curtain window frame element presenting a base portion having a substantial area for engagement with the curtain fabric, a prong concealing and turning portion integral with and bent generally parallel to said base portion and contacting therewith, and an angular glass retaining portion integral with said base portion.

6. A curtain window frame portion presenting in cross section an angular glass-surrounding portion, a base portion presenting a substantial area for engagement with the curtain fabric and integral with said base portion a prong concealing and turning portion bent generally parallel to said base portion and having its edge adjacent said glass-surrounding portion.

7. Curtain window elements including two frames presenting cooperating prongs and prong-receiving apertures, and removable spacing projections operatively interposed between said frames to oppose, prior to removal of such spacing projections, any clenching of said prongs during storage, shipment or handling while said prongs are engaged in said apertures, said spacing projections integral with the prong-providing frame.

8. Curtain window elements including two frames presenting cooperating prongs and prong-receiving apertures, and removable spacing projections operatively interposed between said frames to oppose, prior to removal of such spacing projections, any clenching of said prongs during storage,

shipment or handling while said prongs are engaged in said apertures, said spacing projections readily breakable in their entirety from their carrying part when subjected to bending strains by the operator prior to assembly of the frames in use.

9. A curtain window frame comprising a prong-presenting unit and a prong-receiving unit, each presenting surfaces of substantial width for gripping a curtain therebetween, said prong-receiving unit comprising

ing in cross section, a flange for overlying a portion of a glass adjacent to its edge, a second flange surrounding the edge of said glass, and a reversely bent base flange providing one of said curtain gripping surfaces, said base flange providing prong-bending, prong-clenching and prong-concealing means.

In testimony whereof, I have signed my name to this specification.

RAYMOND CALPIN.
